[57] **CLAIM**

The ornamental design of a bed hand-rail attachment, as shown and described.

DESCRIPTION

FIG. 1 is a perspective view of the embodiment of a bed hand-rail attachment showing my new design;

FIG. 2 is an elevational view of the front side thereof;

FIG. 3 is an elevational view of the back side thereof;

FIG. 4 is an elevational view taken from the right side thereof, the view from the left side being a mirror image of this view;

FIG. 5 is a top plan view thereof;

FIG. 6 is a bottom plan view thereof; and,

FIG. 7 is a perspective view of the bed hand-rail attachment of the invention shown in use in a bed.

The broken line representation of a person and a bed in FIG. 7 is for illustrative purposes only and forms no part of the claimed design.
